CART FOR ELECTRICIANS

William B. Marcell, Fort Myers Beach, Fla., assignor to
Jet Line Products, Inc.

Filed Aug. 28, 1975, Ser. No. 608,556

Term of patent 14 years

Int. Cl. D12—02

U.S. Cl. D12—34

FIG-1

Fig. 2Fig. 3Fig. 4Fig. 5

FIG. 6

FIG. 7

FIG. 8

FIG. 9

FIG. 1 is a front perspective view of a cart for electricians showing my new design, it being understood that the broken lines are for illustrative purposes only;

FIG. 2 is a front perspective view thereof on a reduced scale;

FIG. 3 is a rear perspective view thereof on a reduced scale;

FIG. 4 is a front perspective view of a cart for electricians showing a second embodiment of my new design;

FIG. 5 is a rear perspective view of FIG. 4;

FIG. 6 is a front perspective view of a cart for electricians showing a third embodiment of my new design;

FIG. 7 is a rear perspective view of FIG. 6;

FIG. 8 is a front perspective view of a cart for electricians showing a fourth embodiment of my new design; and

FIG. 9 is a rear perspective view of FIG. 8.

I claim:

The ornamental design for a cart for electricians, substantially as shown and described.
